Primary Examiner — Mitchell I. Siegel(74) Attorney, Agent, or Firm — Klarquist Sparkman, LLP(57) CLAIM

We claim the ornamental design for a golf club head, as shown and described.

DESCRIPTION

FIG. 1 is a perspective view of a golf club head, as viewed from the bottom, rear and one side thereof;

FIG. 2 is a front elevation view thereof;

FIG. 3 is a rear elevation view thereof;

FIG. 4 is a toe side elevation view thereof;

FIG. 5 is a heel side elevation view thereof;

FIG. 6 is a top plan view thereof; and,

FIG. 7 is a bottom plan view thereof.

The broken line shown are included for the purpose of illustrating unclaimed subject matter and forms no part of the claimed design.
